UNITED STATES PATENT OFFICE.

JAMES M. ELDER AND ANDERSON W. MEANS, OF INDIANAPOLIS, INDIANA;
SAID MEANS ASSIGNOR TO SAID ELDER.

FENCE-POST.

No. 804,711.

Specification of Letters Patent.

Patented Nov. 14, 1905.

Application filed May 27, 1905. Serial No. 262,703.

To all whom it may concern:

Be it known that we, JAMES M. ELDER and ANDERSON W. MEANS, citizens of the United States, residing at Indianapolis, in the county 5 of Marion and State of Indiana, have invented certain new and useful Improvements in Fence-Posts; and we do hereby declare the following to be a full, clear, and exact description of the invention, such as will enable 10 others skilled in the art to which it appertains to make and use the same.

Our invention relates to improvements in the manufacture of cement or molded fence-posts.

15 It consists in the molding of the post and the application thereto of certain adjunctive parts of a continuous operation substantially as hereinafter more fully disclosed and particularly pointed out.

20 In the accompanying drawings, Figure 1 is a vertical section of the preferred embodiment of our mold. Fig. 2 is a side view of a completed post, showing one of the stays employed in dotted line. Fig. 2^a is a cross-25 section of the mold. Fig. 3 is an edge view of the stays employed in the construction of the post. Figs. 4, 5, 6, and 7 are separate views of the tool also used in connection with the mold for placing and retaining in place 30 certain adjunctive parts of the prospective post during its formation. Figs. 8 and 9 are views showing principally the fastening and its insertion in post for dividing line-wire. Fig. 10 is a view of one of the corner or gate 35 post wire-attaching bolts in place in the post. Fig. 11 is a detail view of a headed bolt. Figs. 12, 13, 14, 15, and 16 are separate or detached views of a cap, a washer and a nut, adjunctive parts of the post formation, the 40 cap being in side and plan views, and the nut shown in like manner.

In the carrying out of our invention we provide a suitable mold 1, including its palate 2, and form holes in the said palate, as shown, 45 and through which are inserted an equal number of formers 3 with the prospective number of attaching pins or connections for use in organizing the fence. Said mold may be made double, if desired. Upon the formers 3 50 are now placed retainers or washers 5, with their inner edges resting upon shoulders 3^a of said former, and upon the extreme upper pointed ends of said formers are placed caps 6, said ends passing through the apertures 6^a

of the latter to prevent lateral displacement 55 of said caps. A suitable amount of sand and cement 4^a is poured and properly tamped in the mold around the right lined surfaces of said formers—say one inch and a half in depth—Portland cement and fine sharp sand 60 being preferably used.

A stay or reinforcing member, a thin metal strip 7, is now placed in position upon the cement, and upon the member 7 is laid additional sand and cement 8, as previously put 65 into the mold to within about an inch and a half of the top edge of the mold. Upon this additional cement and sand is placed another metal strip 7, the mold now being filled in with further cement and sand clear to its top 70 edge and the whole allowed to stand until the cement has become fully set, after which the post formation is readily removed by lifting out the palate bearing the same, as will be appreciated. It will be understood that the 75 side and ends of the mold which are hinged to the bottom thereof are suitably lowered to permit the removal of the palate with the post. In this type of the post formation the spring-metal staples 9 are used, being suitably gripped by “long-nosed” pliers (not shown) and compressed until the bent free ends of said staples may be passed through the openings formed in the post formation by the use of the formers 3, which of course 80 have been previously withdrawn. The staples are for the attachment of the dividing fence line-wire thereto as in erecting a fence.

In the moldings of a post of the type such as used for fence-corners and to form hinge- 90 posts the very same procedure is adopted with the exception that a different form of retainer is used, nuts 10 being used in lieu of the washers and screw-bolts 11 or 11^a in place of the staples, as shown by Figs. 10 and 11. 95 Said bolts may be hooked at the end, as shown at 11 in Fig. 10, or they may be headed as shown at 11^a in Fig. 11, the latter form being used for attaching a hinge, gate-latch, wire-stretcher, rail-plate, &c.

100 From the foregoing it is believed that advantages of our invention are apparent without further elucidation in that direction herein.

Having thus described our invention, what 105 we claim as new, and desire to secure by Letters Patent, is—

1. A cement fence - post, with chambers

- molded therein, and bolts having their securing-nuts in said chambers.
2. A cement fence - post, with chambers molded therein, retainers arranged in said chambers and means, adapted to engage said retainers, for securing an object to the post.
3. A cement fence - post, with chambers molded therein, retainers arranged in said chambers, and bolts adapted to engage said retainers.
4. A cement fence - post, with chambers molded therein, nuts arranged in said chambers, and bolts adapted to engage said nuts.
5. A cement fence-post, a retainer and a cap molded in said post and forming a chamber therein, and means, adapted to engage said retainer, for securing an object to the post.
6. A cement fence-post, a nut and a cap molded in said post and forming a chamber therein, and a bolt adapted to engage said nut.
7. A cement fence-post, a retainer and a cap molded in said post and forming a chamber therein, said post having a passage leading from said chamber to its outer face, and means adapted to extend through said passage and engage said retainer, for securing an object to the post.
8. A cement fence-post, a retainer and a cap molded in said post and forming a chamber therein, said post having a passage with diverging walls leading from said chamber to its outer face, and means, adapted to extend through said passage and engage said retainer, for securing an object to the post.
- In testimony whereof we affix our signatures in presence of two witnesses.

JAMES M. ELDER.
ANDERSON W. MEANS.
